CLAIM

The ornamental design for an insert with provision for power outlets for a ready-to-assemble furniture grommet, as shown and described.

DESCRIPTION

FIG. 1 is a front elevational view showing my design;

FIG. 2 is a left side elevational view of FIG. 1, the right side view being a mirror image thereof;

FIG. 3 is a rear elevational view of FIG. 1;

FIG. 4 is a top view of FIG. 1;

FIG. 5 is a bottom view of FIG. 1; and,

FIG. 6 is a perspective view of FIG. 1.
